UNITED STATES PATENT OFFICE.

HIRAM V. ALLAM, OF DENVER, COLORADO.

SCREW-HOLDING ATTACHMENT FOR SCREW-DRIVERS.

SPECIFICATION forming part of Letters Patent No. 772,912, dated October 25, 1904.

Application filed April 4, 1904. Serial No. 201,566. (No model.)

To all whom it may concern:

Be it known that I, HIRAM V. ALLAM, a citizen of the United States of America, residing in the city and county of Denver and State of Colorado, have invented certain new and useful Improvements in Screw-Holding Attachments for Screw-Drivers; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to improvements in screw-holding attachments for screw-drivers or devices adapted to be attached to screw-drivers, whereby a screw may be held in proper position when the user of the screw-driver is obliged to reach a considerable distance, making it difficult to start the screw with an instrument of ordinary construction.

Generally speaking, my improved device consists of a tube adjustably connected with a ferrule or sleeve mounted on a reduced portion of the shank of the screw-driver, there being a shoulder at each extremity of the reduced part. The opening through the sleeve is large enough to allow it to pass the shoulders of the screw-driver shank. Within this sleeve or ferrule are placed two sleeve segments or parts which engage a shoulder at the lower extremity of the ferrule, but extend inwardly beyond said shoulder, whereby the ferrule will not pass the shoulders of the screw-driver shank in either direction. Also located within the ferrule is a packing-ring, the tube being threaded in the ferrule, whereby the packing-ring may be made to grasp the shank 40 of the screw-driver more or less tightly, as may be desired. By virtue of this arrangement the screw-holding attachment may be supported in any desired position upon the shank of the instrument. This attachment 45 may also be moved downwardly upon the shank of the screw-driver, so that the latter may be used as if the attachment were not connected therewith or as an ordinary device of its class.

50 Having briefly outlined my improved con-

struction as well as the function it is intended to perform, I will proceed to describe the same in detail, reference being made to the accompanying drawings, in which is illustrated an embodiment thereof.

55 In the drawings, Figure 1 is a view of a screw-driver equipped with my improvements, the same being shown in use or in connection with a screw after the latter has been moved out of the screw-holding tube. Fig. 2 is a view illustrating a screw-driver provided with the attachment, the screw being partly inserted, but having a portion of it still in the tube of the attachment. Fig. 3 shows the device with a modified form of screw-driver. Fig. 4 is a fragmentary detail view with the parts shown on a larger scale. Fig. 5 is a section taken on the line 5-5, Fig. 4. Fig. 6 is a detail view of the divided ring forming a part of my improved attachment, the parts being shown on a larger scale.

60 The same reference characters indicate the same parts in all the views.

Let A designate the shank of a screw-driver having a reduced part A' provided with shoulders A² at the opposite extremities of the reduced shank part A'. Mounted on the shank part A' is a sleeve B, which is considerably larger than the reduced part A', but whose lower extremity is provided with an interiorly-projecting circular flange B', forming a narrow shoulder adapted to prevent the sleeve-segments C from dropping through the bottom of the sleeve when placed therein. The opening B³ in the bottom of the sleeve is 65 of sufficient size to allow the sleeve to pass over either shoulder A². Above the sleeve-segments is located a packing-ring D, composed of leather or other suitable material. The upper extremity of the sleeve B is interiorly threaded, and into it is screwed the lower extremity of a screw-holding tube E, which is interiorly beveled, as shown at E', whereby as the tube is screwed against the packing-ring D the latter is forced inwardly 70 against the shank of the screw-driver, whereby the tension of the device on the shank may be regulated at will. The object of an arrangement of this kind will be readily understood, since it is necessary that the device be 75

slipped downwardly on the shank of the screw-driver far enough to allow the latter to be used as an ordinary device when there is no necessity for using the attachment. When, 5 however, the attachment is needed, it is necessary to move it toward the driving end of the screw-driver far enough so that the tube E shall project beyond the nick-engaging extremity of the driver. In this event it is evident 10 that some provision must be made to prevent the device from slipping down on the shank from this position of adjustment. The mechanism heretofore described performs this function. Moreover, it is not desirable that 15 the device should slip down upon the shank of the driver farther than is necessary, and for this reason the divided sleeve C is employed, whereby the device cannot be moved downwardly or toward the handle of the screw-driver farther than the lower shoulder A².

From the foregoing description the use and operation of my improved device will be readily understood. When it is in use, it should be moved to the position shown in Fig. 2, whereby the tube E projects beyond the upper extremity of the nick-engaging end of the screw-driver. The screw is then dropped into the tube, which will support it in position until its extremity is started into the 30 wood part F. If it is not desired to use the device, it may be moved downwardly to its limit of movement, as shown in Fig. 1. In this event the nick-engaging end of the screw-driver protrudes beyond the tube E, and the 35 instrument is capable of use the same as if the attachment were not in place.

In the construction shown in Fig. 3 the nick-engaging extremity of the screw-driver is formed flat and is provided with a tongue 40 A³ to fit the groove or nick in the screw end.

Having thus described my invention, what I claim is—

1. The combination with a screw-driver having a reduced portion and shoulders at the opposite extremities of the reduced portion, 45 of a sleeve mounted on said reduced portion and having an opening interiorly threaded in the upper extremity, its lower extremity being partly closed, a divided ring located within the sleeve, a packing-ring located in the sleeve 50 above the divided ring, an open-ended tube exteriorly threaded to enter the threaded extremity of the sleeve and having its inner extremity beveled to force the packing-ring against the shank of the screw-driver for the 55 purpose set forth.

2. In a device of the class described, the combination with a screw-driver having a reduced portion and having shoulders at the opposite extremities of said reduced portion, a 60 short sleeve mounted on said reduced portion of the screw-driver, said sleeve being open and interiorly threaded at its upper extremity, and partly closed at its lower extremity, the opening, however, in its lower extremity being 65 large enough to allow it to slip over the shoulders of the shank, a divided ring placed within the sleeve and resting upon the lower extremity thereof but projecting inwardly to close the opening in the bottom of the sleeve 70 sufficiently to prevent the sleeve from passing beyond the shoulders of the screw-driver shank, a packing-ring inserted in the sleeve above the ring-segments, and a screw-holding tube threaded in the upper extremity of 75 the sleeve and having its lower extremity interiorly beveled for the purpose set forth.

In testimony whereof I affix my signature in presence of two witnesses.

HIRAM V. ALLAM.
